UNITED STATES PATENT OFFICE.

NELSON MUSLAR, OF WORCESTER, MASSACHUSETTS, ASSIGNOR, BY MESNE ASSIGNMENTS, TO ROYAL LABELING MACHINE COMPANY, INCORPORATED.

LABELING MACHINE.

Application filed February 2, 1920. Serial No. 355,874.

To all whom it may concern:

Be it known that I, NELSON MUSLAR, a citizen of the United States, residing at Worcester, county of Worcester, State of Massachusetts, have invented an Improvement in Labeling Machines, of which the following description, in connection with the accompanying drawing, is a specification, like characters on the drawing representing like parts.

This invention relates to a machine for applying labels to bottles, cans, jars, and other similar containers, and has for its object to provide an improved machine of this character which is relatively simple in its construction, which is accurate in its operation, and which has various other advantages, all as will be more fully hereinafter set forth.

In order to give an understanding of my invention, I have illustrated in the drawings a selected embodiment thereof which will now be described, after which the novel features will be pointed out in the appended claims.

Fig. 1 is a side view of a machine embodying my invention;

Fig. 2 is a front view thereof;

Fig. 3 is a section on the line 3—3, Fig. 1;

Fig. 4 is a view on substantially the line 4—4, Fig. 1, looking to the right, and showing the wipers and their actuating mechanism;

Fig. 5 is a fragmentary sectional view showing the manner in which the label is applied to the bottle;

Fig. 6 is a view of the wipers showing them in action.

My improved machine comprises a table on which the bottle, jar, or other container is supported, a magazine for containing the labels, which magazine is open at the bottom, and means for applying glue or other adhesive to the bottom label in the magazine and withdrawing said label through the open bottom of the magazine and applying it to the container which for convenience will be hereinafter referred to as a bottle, although I desire it to be understood that the device can be used for applying labels to other containers than bottles.

The bottle on which the label is to be applied is indicated at 1. It is supported on a table or support 2 which will be properly shaped to receive the particular container

to be labeled. This support or table 2 is shown as mounted on posts 3 which rise from a bracket 4 that is attached to and extends from the end of a supporting arm 5. This arm 5 is mounted on a post or standard 6 forming part of the frame of the machine, said standard rising from a suitable base 7.

The labels which are to be applied to the bottle are indicated at 70. They are stacked in a magazine indicated generally 8 which is provided with an open bottom through which the labels may be successively withdrawn. The magazine is supported on an arm or bracket 9 also secured to the standard or frame 6.

The magazine may be constructed in various ways without departing from the invention. As herein shown it is made with end and side walls which are adjustable relative to each other so as to accommodate labels of different sizes. The side walls of the magazine are indicated at 10, and the end walls at 11 and 12. The end wall 11 is formed on a member 13 which is supported on two rods 14 that extend from the arm 9. The front wall 12 is carried by a front member 15 also mounted on the rods 14, and the member 15 is adjustable on the rods so that it can be moved toward and from the member 13. Said member 15 is held in adjusted position by means of a set-screw 16. The side walls 10 are situated between the front and end walls and are constructed to be adjusted toward and from each other. This is provided for by means of an adjusting screw 17 which is rotatably mounted in bearings 18 carried by the rear member 13, said adjusting screw having right and left hand screw-threads that have screw-threaded engagement with the side walls 10 so that as the screw is turned said side walls will be adjusted toward and from each other. The side and end walls of the magazine have fingers 19 depending therefrom, the ends of

which are bent inwardly sufficiently to engage the edges of the labels and hold them in the magazine. These fingers, however, permit the ready removal of the bottom label from the magazine.

The magazine is provided with a follower 20 which rests on the top of the stack of labels. This follower is adjustable vertically so as to permit it to move downwardly as the labels are withdrawn. Said follower has a stem 21 rising therefrom which ex-

tends through a bracket 22 that is adjustably carried by an arm 23 extending from a post 24 which rises from the arm 9. This bracket 22 has a post or pin 25 rising therefrom 5 which extends through an aperture in a clamping arm 26 that bears on the upper end of the stem 21. A resilient connection between the stem 21 and the clamping arm 26 is provided in the form of a spring-supporting pin 27 carried by the stem and extending from the end thereof and against which the clamping arm 26 rests. Since the pressure of the stem against the clamping arm is at the end of the arm, such pressure will tend 10 to swing the arm upwardly, thus causing it to grip the post 25. As the labels in the magazine are used the operator will keep sliding the clamping arm 26 downwardly on the post thereby to keep the follower 15 clamped against the stack of labels.

The machine herein shown comprises a combined glue-applying and transferring element constructed to apply glue to the bottom label in the magazine and to transfer 25 said label into a position adjacent the bottle 1, and it also comprises a means for placing the glued label on the bottle and affixing it thereto by pressure. The combined glue-applying and transferring element is indicated at 28. It is herein shown as a bifurcated platform which is movable vertically from a position close to the table 2 to the bottom of the magazine. Means are provided for coating this element 28 with glue 30 so that in its upward movement the glued coated surface thereof is brought against the bottom label in the magazine thereby applying glue to said label. After this element has been brought into contact with the bottom label in the magazine, it is moved downwardly into a position adjacent the bottle, and during such movement the bottom label 35 adheres to the transferring element and is carried thereby into a position above the bottle. When in this position a label-affixing member indicated at 29 moves downwardly between the arms of the transferring element 28 and carries the label through the space between said arms and onto the bottle 1 40 where it is held while some wiper elements engage the label and affix it permanently to the bottle.

The transferring element 28 is carried by two vertically-moving bars 30 which are 45 guided in their vertical movement in suitable guides 31 formed in the forked guiding frame 32, the lower end 33 of which is secured to the base 7. These two bars 30 are connected at their lower end by the bridge member 34 and the latter is connected by 50 means of a connecting rod 35 to a crank arm 36 that is fast on a driving shaft 37 that is journaled in suitable bearings in the frame. The connecting rod 35 is pivoted to the yoke 60 55 34 at 38. The rotation of the shaft 37, there-

fore, will operate through the crank 36 and connecting rod 35 to move the transferring element 28 vertically, and the movement is sufficient to carry it from a position immediately above the bottle into the dotted line 70 position Fig. 5, in which it contacts with the bottom label in the magazine.

The glue is applied to the transferring element 28 by means of a glue-roll 39. This roll is mounted on a shaft 40 which is journaled in two arms 41 that are pivotally connected to the upper end of two arms 42. These arms 42 are fast on a rock-shaft 43 journaled in suitable bearings in the frame, and said rock-shaft has fast thereon an arm 44 carrying a roll 45 adapted to be actuated by a cam 46 on a cam shaft 47 that is journaled in suitable bearings in the frame. This cam shaft 47 is geared to the driving shaft 37 by means of bevel gears 48. The roll 45 is held against the cam 46 by means of a spring 49 that acts on the arm 44. The rotation of the cam 46 will vibrate the arm 44 thereby swinging the arms 42 and carrying the glue-roll 39 from the full to the dotted line position Fig. 5. The glue-roll receives its glue from a glue-pot 50 which is supported on the arm 5. This glue-pot has a roll 51 rotating therein with which the glue-roll 39 comes in contact upon the backward movement of the levers 42, and during such contact, glue is transferred from the roll 51 to the glue-roll 39. During the forward movement of the arms 42 this glue-roll 39 is carried across the upper face of 100 the transferring element 28, as indicated in full lines Fig. 5, and thus glue is applied to such upper face.

The arms 41 in which the glue-roll is mounted are pivoted to the arms 42 at 52, and said arms 41 are acted on by pulling springs 53.

The application of the glue to the transferring member 28 occurs while said member is rising toward the magazine, and the yielding connection between the glue-roll 39 and the arms 42 permits such upward movement of the transferring element while said roll is moving across the same.

The roll 51 is positively driven and as it dips into the glue in the glue-pot 50, the surface thereof will be constantly coated with glue.

57 indicates a scraper which can be adjusted so as to gage the thickness of the film of glue which is carried by the roll 51. For positively driving this roll 51, I have provided the shaft 55 thereof with a driving pulley 58 over which runs a chain or belt 59 that is driven by a pulley or sprocket wheel 60 fast on the cam shaft 47.

Means are provided for positively rotating the glue-roll 39 when the latter has been moved backwardly into contact with the roll 51. For this purpose the shaft 40 of 130

the glue-roll 39 has a gear 54 fast thereon which is adapted to mesh with a gear 56 fast on the shaft 55 of the roll 51 when the arms 42 are swung into their rearmost position. Therefore, when the arms are in a position to bring the glue-roll 39 into contact with the roll 51, said glue-roll will be positively driven and will, therefore, be uniformly supplied with a coating of glue. 5

10 The cam 46 may be so shaped as to produce a dwell in the movement of the arms 42 while the glue-roll is in contact with the roll 51 so as to give ample time to provide a thorough coating of glue to the glue-roll. 15

15 From the above it will be seen that during the upward movement of the transferring element 28 it is provided with a coating of glue, and when it reaches the upper limit of its movement, it is brought into 20 contact with the lower label in the magazine and on its downward movement it withdraws said label from the magazine and carries it into position directly above and adjacent the bottle. 25

25 The element 29 which places the label against the bottle is in the form of a narrow blade adapted to pass through the bifurcation of the transferring element 29. This member 29 is carried by an arm 61 30 which is pivoted to the arm 5 at 62. Said arm 61 has a rod 63 pivotally connected thereto and depending therefrom, which rod telescopes into a member 64 that is pivotally connected at 65 to a cam-operated 35 lever 66. This lever is pivoted to the frame at 67 and carries a roll 68 which is acted on by a cam 69 carried by the cam shaft 47. A spring 70 holds the roll against the cam 69. The rod 63 has a collar 71 thereon 40 and a spring 72 is confined between the collar and the member 64, said spring constituting a yielding connection between the rod 63 and the cam lever 66. The cam 69 thus gives a swinging movement to the 45 member 29, and this movement is such as to carry it from the position shown in Fig. 5, in which it contacts with the bottle 1, into a substantially vertical position back of the line of travel of the transferring element 28. The member 29 will be in its 50 rearmost position while the transferring element 28 is moving downwardly with the label attached, and when said transferring element comes into position shown in Fig. 5, 1, the member 29 is swung forwardly, and during its movement will be carried down between the arms of the member 28, as shown in Fig. 5, and by this movement will engage the label carried on top of the member 28 and draw the latter through the bifurcation thereof and press it against the bottle 1. 55

60 After the label has thus been pressed against the bottle with the glued side of the label against the bottle, said label is acted upon by wipers which have a wiping engagement therewith and which firmly affix it to the bottle. There are two such wipers and they are indicated at 73. Each wiper is of some flexible material such as leather or felt 70 and is carried by a holder 74 mounted on the end of an arm 75. The arms 75 are pivoted at 76 to a carrier 77 that is mounted for vertical movement on two guiding posts 78 carried by the frame. Each arm 75 is acted 75 upon by a pulling spring 79 which tends to hold said arm in its open or retracted position shown in Fig. 4. The carrier 77 is moved vertically after the label has been placed on the bottle thereby to carry the 80 wipers above the label and then the wipers are moved toward each other into the position shown in Fig. 6, and then are moved downwardly, during which downward movement they have a wiping action against the 85 edges of the label and paste or glue it to the bottle. The vertical movement of the carrier 77 is derived from a crank 80 on the driving shaft 37, said crank being connected to the carrier by means of a connecting rod 90 81. The movement of the wipers toward each other is effected by means of a cam member 82 which is slidably mounted in ways 83 formed in the carrier 77 and is given a vertical movement from a crank 84 of the 95 driving shaft 37, said crank being connected to the cam member by means of a connecting rod 85. The two cranks 80 and 84 are set at different angles with the result that the cam member 82 will have a movement relative to the carrier 77. The cam member 82 is provided with two cam surfaces 86 which act against rolls 87 formed on the lower ends of the arms 75, so that when the cam 100 82 is raised in the carrier 77, the cam surfaces 86 acting against the rolls 87 will throw the wipers toward each other. The cam 82 is also provided with a recess 88 in each side situated below the cam surface 86. 105 The construction of the cam 82 and its mode of operation together with that of the carrier 77 are such that when the carrier 77 is moved upwardly to carry the wipers 73 above the bottle, the wipers will remain in open position, but when the carrier reaches the upper limit of its movement the cam 82 moves upwardly relative to the carrier, thus 110 swinging the arms 75 and moving the wipers 73 toward each other. The wipers will be 115 held in this position as the carrier moves downwardly until said wipers come into contact with the label on the bottle. At this time the cam 82 has moved relative to the carrier so as to permit the rolls 87 to drop 120 into the recesses 88. This allows a separating movement of the wipers which draws them away from each other across the label. After this separating movement the carrier 125 and cam move downwardly together so that 130

the wipers are wiped over the sides of the bottle, and in doing so wipe or paste the edges of the label firmly against the bottle. When the carrier has reached its lower position, the cam 82 has moved relative thereto so as to permit the wipers to be opened away from each other, as shown in Fig. 4.

The construction of the machine is such that the complete cycle of operations is performed during each rotation of the shaft 37. This shaft may be driven from any suitable source of power. I have herein shown a driving pulley 89 as loosely mounted thereon and as adapted to be clutched thereto by any suitable one-revolution clutch indicated generally at 90. This clutch is shown as actuated by a treadle 91 pivoted to the frame at 92. The treadle is connected by a connection 93 with a lever 94 which in turn is pivoted to the frame at 95 and is connected to the clutch by a connection 96. The clutch is such that when the treadle is depressed it will be thrown into engagement and upon releasing the treadle the clutch will be automatically disengaged when the shaft has made one revolution. Inasmuch as one-revolution clutches are in common use and any suitable one-revolution clutch may be employed, I have not thought it necessary to illustrate any particular clutch in detail.

While the operation of the device will be apparent from the above description, yet it may be helpful to give a brief summary of such operations.

Fig. 1 shows the machine with the parts in the position they assume when said machine is at rest. The operator first places a bottle on the table 2, as shown in Fig. 1, and then depresses the treadle 91. This sets the shaft 37 in rotation, and during such rotation, the transferring element 28 is moved upwardly against the bottom label in the magazine, and during such upward movement the glue roll 39 swings back and forth across the upper face of said transferring element, thus applying a coating of glue thereto. When the glue-coated transferring element 28 is pressed against the lower label in the magazine, such label will not only receive a coating of glue but will also adhere to the transferring element so that upon the downward movement of said element, the label is carried with it. During the upward and return movement of the transferring element 28, the member 29 is swung backwardly out of the way. When the transferring element reaches its lowest position, the member 29 is swung forwardly and engages the top of the label and forces said label down through the opening between the two parts of the transferring element 28 and carries said label onto the bottle, as indicated in Fig. 5. During this time the wipers 73 have been moved upwardly to a position above the bottle and

they are then swung inwardly and brought against the label on the bottle, as shown in Fig. 6. Said wipers after thus engaging the bottle are separated slightly by reason of the rolls 87 dropping into the notches 88 and thus have a wiping movement across the side of the bottle, after which said wipers are moved downwardly so as to wipe the edges of the label around the sides of the bottle and complete the labeling operation. The wipers are carried down into the position shown in Fig. 1, at which time the machine is brought to rest.

Means are provided for moving the magazine bodily vertically on the bracket 9 so as to elevate it into a position out of reach of the member 28 if it is desired to stop the labeling operation without stopping the machine. This is provided for by supporting the arms 14 in a bracket or casting 97 which is slidable vertically on posts 98 carried by the arm 9. This bracket 97 has a lever 99 pivoted thereto at 100, and said lever is provided with an extension 101 which is pivotally connected to a link 102 that is pivoted to the arm at 103. The link 102 and extension 101 form a toggle lever which can be straightened by raising the lever 99. When it is desired to place the magazine in inoperative position, the lever 99 will be raised thereby lifting the magazine and its supporting bracket 97 bodily on the posts 98 and elevating the bracket into a position where it is out of reach of the transferring element 28.

I claim:

1. In a labeling machine, the combination with a bottle-supporting table, of means to place a glued label on a bottle on said table, a vertically-movable carrier, a pair of wipers mounted thereon for movement relative to each other, means to move the carrier vertically thereby to carry the wipers from a position above the table to one beneath the table, and means mounted on said carrier movable relative thereto to give the wipers a relative movement as the carrier is being moved.

2. In a labeling machine, the combination with a bottle-supporting table, of means to place a glued label on a bottle on said table, a vertically-movable carrier, a pair of wipers mounted thereon for movement toward and from each other, means to move the carrier vertically thereby to carry the wipers from a position beneath the table to a position above the table and then back to the initial position, and means mounted on said carrier to cause said wipers to be separated from each other during their upward movement and to be moved into position to engage the label during their downward movement and to have a relative separating movement while in engagement with the label.

3. In a labeling machine, the combination

- with a bottle-supporting table, of means to place a glued label on a bottle on said table, a vertically-movable carrier, a pair of wipers pivotally mounted thereon, means to move the carrier vertically thereby to carry the wipers from a position above the table to one beneath the table, a cam on said carrier and movable vertically relative thereto for controlling the movements of the wipers. 5
- 10 4. In a labeling machine, the combination with a bottle-supporting table, of means to place a glued label on a bottle on said table, a vertically-movable carrier, a pair of wipers pivoted thereon, a cam movably mounted on the carrier for controlling the position of the wipers relative to each other, a crank shaft having two cranks thereon, one connected to the carrier and the other to the cam. 15
- 15 5. In a labeling machine, the combination with a bottle-supporting table, of means to place a glued label on a bottle on said table, a vertically-movable carrier, a pair of wipers pivotally mounted thereon, a crank shaft connected to said carrier for giving it its vertical movement, a cam mounted on the carrier and operating to control the position of the wipers relative to each other, and means actuated by the crank shaft to move the cam relative to the carrier. 20
- 20 6. In a labeling machine, the combination with a bottle-supporting table, of means to place a glued label on a bottle on said table, a pair of wipers, means to move the wipers downwardly to cause them to have a wiping action on the label, and means to give the wipers an intermittent separating movement during their engagement with the label. 25
- 25 7. In a bottle labeling machine, the combination with a bottle-supporting table, of means to place a glued label on a bottle on said table, a vertically-movable carrier, two rock shafts pivoted to the carrier, a wiper carried by each rock shaft, each rock shaft also having a depending arm, a cam mounted on the carrier and situated between said arms and operating by its movement relative to the carrier to move the wipers relative to each other, and a crank shaft having two cranks, one connected to the carrier and the other to the cam. 30
- 30 8. In a labeling machine, the combination with a bottle-supporting table, of means to place a glued label on a bottle on said table, a vertically-movable carrier, a pair of wipers mounted thereon for movement relative to each other, means to move the carrier vertically thereby to carry the wipers from a position above the table to one beneath the table, a cam on said carrier for controlling the movement of the wipers relative to each other, and means for actuating said cam. 35
- 35 9. In a labeling machine, the combination with a bottle-supporting table to support a bottle in horizontal position, of means to place a glued label on a bottle on said table, a carrier, a pair of wipers mounted thereon for movement toward and from each other, means to move the carrier vertically to carry the wipers from a position beneath the table to a position above the table and then back to the initial position, and means carried by the carrier but movable relative thereto to cause said wipers to be separated from each other during their upward movement and to be moved into position to engage the label during their downward movement. 40
- 40 10. In a labeling machine, the combination with a bottle-supporting table to support a bottle in horizontal position, of means to place a glued label on a bottle on said table, a carrier, a pair of wipers mounted thereon for movement toward and from each other, means to move the carrier vertically to carry the wipers from a position beneath the table to a position above the table and then back to the initial position, and means mounted on the carrier to cause said wipers to be separated from each other during their upward movement and to be moved into position to engage the label during their downward movement and to have a relative separating movement while in engagement with the label. 45
- 45 50 In testimony whereof, I have signed my name to this specification.

NELSON MUSLAR.
